FIG. 1

FIG. 2

FIG. 3

FIG. 4

FIG. 5

FIG. 6

FIG. 1 is a front perspective view of a chair showing my design wherein the seat and backrest cushions are tufted;

FIG. 2 is an upper perspective view of the chair of FIG. 1 taken from the right rear side, the left side having the same design as the right side;

FIG. 3 is an upper perspective view of a modification of the chair of FIG. 1 wherein the cushions are not tufted, taken from the left rear side;

FIG. 4 is an upper perspective view of the inventive chair with arms, taken from the right front side;

FIG. 5 is a perspective view of the chair of FIG. 4, taken from the right rear side, the left side being of the same design as the right side; and

FIG. 6 is a perspective view of another modification of the chair, with arms and without tufting of the cushions, taken from the left rear side, the remainder of the design being the same as that shown in FIGS. 4 and 5 except for the tufting.

I claim:

The ornamental design for a lounge chair with low back, as shown and described.
